UNITED STATES PATENT OFFICE

2,446,436

BEAM ANTENNA SYSTEM

Charles L. Rouault, Schenectady, N. Y., assignor
to General Electric Company, a corporation of
New York

Application April 19, 1943, Serial No. 483,555

6 Claims. (Cl. 250—33)

1

This invention relates to antenna systems and more particularly to antenna systems adapted for radiating sharply directive beams of radio frequency energy.

Systems have been proposed in which periodic pulses of short wave oscillations have been radiated into space and an echo of each pulse has been received in the period prior to the next succeeding pulse. In communication systems of this type, there have been provided antenna systems from which are radiated periodic pulses and by which the echoes are intercepted. Antenna systems for such purposes are usually of a type projecting a sharp beam of radio energy into space and are usually provided with a reflector which may be of any suitable surface of revolution but are most commonly of paraboloid form. The beam is projected at a small angle to the axis of the reflector and the radiator is located at substantially the focal point on the axis of the reflector in order to rotate the beam about the surface of a cone, the axis of which is the axis of the reflector. The radiating system including the reflector is arranged to be oriented both in elevation and in azimuth by suitable mechanical means so that the axis of the paraboloid can be directed at a remote object such as a target and maintained so oriented.

Such systems have been generally described and claimed in application, Serial No. 482,403, to Donald E. Norgaard, filed April 9, 1943, and application, Serial No. 414,126, of Sidney Godet, filed October 8, 1942, now Patent No. 2,412,612, granted December 17, 1946, both of which applications are assigned to the same assignee as the present invention.

It is an object of my invention to provide a new and improved antenna system for such systems of communication.

It is another object of my invention to provide a search antenna for such a system which is simple in form, easy of manufacture and assembly, relatively inexpensive, and so arranged that the radiating parts are not subject to any appreciable centrifugal force.

The features of my invention which I believe to be novel are set forth with particularity in the appended claims. My invention itself, both as to its organization and manner of operation, together with further objects and advantages thereof may best be understood by reference to the following description taken in connection with the accompanying drawing in which Fig. 1 is a sectional side elevational view of apparatus embodying the principles of my invention, and Fig. 2 is

2

an enlarged view of the antenna element and associated reflector element shown in Fig. 1.

In the accompanying drawing, there is shown an antenna system comprising a paraboloid reflector 10, an antenna member 11 and a reflector member 12. The antenna member 11 is of the dipole type including substantially collinear or axially aligned elements 13 and 14. The dipole is located at or near the focus of the paraboloid reflector and the axis of the reflector 10 passes through the dipole at or near the midpoint thereof. While there is illustrated a reflector element 12, it will be understood that the element 12 may be omitted, if desired. However, the reflector element 12 reflects energy radiated directly outwardly from the antenna element 11 into the paraboloid reflector 10 so that a sharper beam results when the reflector element 12 is used.

Means is provided for exciting the antenna element 11. This means comprises a source of signal energy which may be considered to be included in the box indicated by numeral 15, an open transmission line 16 and a concentric transmission line 17, the latter comprising an inner conductor 18, represented by the dotted lines in Fig. 1, and an outer cylindrical conductor or tube 19 through which the inner conductor extends. The inner conductor extends along the axis of the paraboloid.

30 The source of signal energy or transmitter contained within the box 15 produces pulses of oscillations of high frequency energy and supplies them to the transmission line 16. The pulses are transferred to the concentric transmission line 35 section 17 through a suitable type of rotating joint, indicated by the numeral 20. The antenna array comprising the elements 11 and 12 also receives echo pulses and supplies them to a suitable pulse receiver which may also be considered 40 to be contained within the box 15.

Means is provided for shifting the antenna beam pattern from coincidence with the axis of the reflector and for rotating the antenna assembly so that a rotating beam is projected into space. In the illustrative form of my invention, the dipole is tilted, that is, disposed at an angle of other than 90°, with respect to the axis of the paraboloid reflector. This arrangement causes the projected beam to have an angle of a few degrees with respect to the paraboloid axis. The beam shift may be increased further by unbalancing the currents in the antenna elements 13 and 14. It is well known that in order to have balanced current in the arms or elements of a dipole when those arms or elements are of equal

length, a cylinder of approximately one-quarter wave length may be attached to the end of a concentric transmission line used for exciting the dipole, the cylinder being concentrically disposed with and surrounding the transmission line, open at the radiating end of the line, and attached to the outer conductor of the line at the other end. In the form of my invention described herein no such line balancing arrangement is employed so that the means for conducting the energy to be radiated from the transmission line 16 to the antenna member 11 consists only of the concentric transmission line 17 and the rotating joint 20. Omission of the line balancing cylinder thus causes further beam shift. If still additional beam shift is required the arms or elements 13 and 14 of the antenna member 11 may be made of different lengths, as shown in the drawing.

The above described antenna array is not my invention, but is described and claimed in copending application Serial No. 485,601 of B. P. Brown, filed May 4, 1943, and assigned to the same assignee as the present invention.

In order to permit the determination of the elevation and azimuth of the object from which echoes are received, it is desirable to rotate the displaced pattern about the axis of the paraboloid reflector. For this purpose there is provided a suitable motor 21 receiving electrical energy from a suitable source, not shown, and carried by the base plate 36 attached to the paraboloid reflector in any suitable manner. The motor is operatively connected to the outer conductor 19 through suitable gears 22 and 23 carried by the shaft of the motor and the outer conductor or tube 19 respectively. The rotation producing means and the transmission line 17 are mounted as shown at the center of the paraboloid reflector.

Because of the mechanical couple resulting from the unbalanced disposition of the dipole there results a tendency of the parts of the antenna assembly to "whip" during rotation. In order to minimize the effects of centrifugal force, the transmission line section 17 is supported as close as practicable to the dipole. For this purpose there has been provided a conically shaped support 25 located at the center of the paraboloid reflector and attached to the base 36 at the large end. Suitable bearing means 26 is provided at the small end of the cone. If desired, a bearing may also be provided where transmission line 17 passes through the supporting structure. At any rate, the transmission line section 17 is preferably supported at two points, although some additional support is provided through the intermeshing gears. It will be noted further that the conical member 25 and the base plate 36, serve as a housing for the gears.

In order to obtain intelligence which may be employed to cause the antenna system, including the paraboloid reflector, to follow the target or source of echo, there has been shown a two-phase alternator 28 suitably carried by the paraboloid reflector, as on the base plate 36, and caused to rotate by means of a suitable gear 29 attached to the shaft of the alternator and meshing with the pinion or gear 23. The output of the alternator is utilized to energize suitable elevation and azimuth controlling mechanism in the manner described in the above identified copending applications of Donald E. Norgaard and Sidney Godet.

As shown in Fig. 2, means is provided for connecting the elements 13 and 14 of the antenna member 11 to the transmission line members 18 and 19. The shorter member 14 may be connect-

ed directly to the outer conductor 19 in any desired fashion, as by welding, for example. Means is provided for passing the longer element 13 through the outer conductor 19 into engagement with the conductor 18 and for securing the element 13 to the outer conductor in such a manner as to lend support to the inner conductor and thereby minimize the effects of centrifugal force on the inner conductor and the reflecting member 12. The means connecting the elements 13 and the outer conductor 19, of course, is electrically insulative. In the form of my invention illustrated herein, this purpose is accomplished by providing a stud 30 having a threaded laterally extending portion 31 adapted to engage the threads of a suitably tapped bore in the end of the arm 13. An insulating member 32 is retained within or adjacent to an opening 37 in the outer member 19 between the stud 30 and end of the arm 13. For example, the edge of the member 32 may be encircled by a metal washer 32a and the outer edge of the member or washer 32a may be engaged by a flanged member 33 having internal threads engaging suitable threads in the outer surface of the washer 32a. The inner end of the stud 30 is securely fastened to the inner conductor 18 as by means of a suitably threaded fastening member 34 passing through a suitable opening in the conductor 18 into suitable threaded engagement with the bore in the stud 30. The arm 13 is shown bent at the inner end thereof in order to approach the inner conductor at right angles thereto for convenience of assembly. With this arrangement, the stud may be fastened in position, the insulative washer applied over the threaded end 31 of the stud and the flanged member 33 fastened in place. The arm 13 may then be screwed onto the lateral portion 31 of the stud. The reflector member 12 may be secured to the end of the inner conductor 18 in any suitable manner as by means of the threaded fastening member 35. With this arrangement the inner conductor is maintained in coaxial alignment with the outer conductor during rotation of the antenna system.

The mechanical details of the system described above provide an arrangement easy of assembly or disassembly. As shown in Fig. 2, the outer end of the outer conductor 19 is cut off at a substantial angle to its axis (greater than the angle of the dipole to the axis of conductor 19) and the dipole arm 14 is connected to conductor 19 adjacent the shorter portion or side thereof. The opening 37 through which the arm 13 passes is in the longer portion or side of conductor 19 and is in approximate alignment with the axis of arm 14 so that arm 13 may engage inner conductor 18 in substantial alignment with arm 14. The above features result in ready access to fastening means 34 without disassembly of the system.

While I have shown and described a particular embodiment of my invention, it will be obvious to those skilled in the art that changes and modifications may be made without departing from my invention in its broader aspects, and I, therefore, aim in the appended claims to cover all such changes and modifications as fall within the true spirit and scope of my invention.

What I claim as new and desire to secure by Letters Patent of the United States is:

1. In an antenna assembly comprising a dipole having a pair of substantially axially aligned arms and a coaxial transmission line having inner and outer concentrically disposed conductors for energizing said dipole, one of said arms being secured

to the outer conductor of said line at the end thereof, means for securing the other of said arms to the inner conductor of said line near said end, means for rotating said transmission line at high speed, and supporting means for securing said other arm in fixed position with respect to said outer conductor, thereby to support said inner conductor in substantially coaxial alignment with said outer conductor against the effects of centrifugal force during said rotation at high speed.

2. In an antenna assembly comprising a dipole having a pair of substantially axially aligned arms and a coaxial transmission line having inner and outer concentrically arranged conductors for energizing said dipole, one of said arms being secured to the outer conductor of said line at the end thereof, means for securing the other of said arms to the inner conductor of said line near said end, means for rotating said transmission line at high speed, and an insulating member secured to said outer conductor, said other arm also being secured to said insulating member, said other arm being supported fixedly with respect to said outer conductor through said insulating member, whereby said inner conductor is maintained in substantially coaxial alignment with said outer conductor against the effects of centrifugal force during said rotation at high speed.

3. In an antenna assembly comprising a dipole having a pair of substantially axially aligned arms and a coaxial transmission line having inner and outer concentrically disposed conductors for energizing said dipole means for rotating said transmission line at high speed, one of said arms being secured to the outer conductor of said line at the end thereof, said outer conductor having an opening therethrough and near the end thereof, and an insulating member secured at said opening, said insulating member having an opening therethrough which is smaller than the opening in said outer conductor and substantially coaxial therewith, a portion of said other arm passing through said opening in said insulating member and being secured to said inner conductor, said other arm also being secured to said insulating member and supported fixedly with respect to said outer conductor through said insulating member, whereby said inner conductor is maintained in coaxial alignment with respect to said outer conductor against the effects of centrifugal force during said rotation at high speed.

4. In an antenna system comprising a dipole having a pair of substantially colinear arms and a coaxial transmission line having inner and outer concentrically disposed conductors for energizing said dipole means for rotating said transmission line at high speed, one arm of said dipole being fastened to the outer of said conductors at the end thereof, said outer conductor having an opening therethrough diametrically opposite said one arm and in approximate alignment therewith, the other arm of said dipole having a portion extending through said opening into electrical connection with the inner of said conductors, and insulating means arranged to locate positively said other arm and said outer conductor whereby said

conductors are also located positively with respect to each other and relative motion therebetween, due to the effects of centrifugal force is minimized during said rotation at high speed.

- 5. In an antenna system comprising a dipole having a pair of substantially colinear arms and a coaxial transmission line having inner and outer concentrically disposed conductors for energizing said dipole, an end of said outer conductor being cut off at a substantial angle to the axis thereof, one arm of said dipole being fastened to said outer conductor adjacent the shorter side thereof and at an angle to the axis of said conductors, the last mentioned angle being substantially less than the angle at which said outer conductor is cut, said outer member having an opening therethrough in substantial alignment with the axis of said one arm, the other arm of said dipole having a portion extending through said opening into electrical engagement with said inner conductor and in substantial axial alignment with said one arm, fastening means for securing said other arm to said inner conductor in substantial alignment with said one arm and beyond the shorter side of said outer conductor whereby said fastening means is always accessible without disassembly of said system.
- 6. In an antenna system comprising a dipole having a pair of substantially colinear arms and a coaxial transmission line having inner and outer concentrically disposed conductors for energizing said dipole, an end of said outer conductor being cut off at a substantial angle to the axis thereof, one arm of said dipole being fastened to said outer conductor adjacent the shorter side thereof and at an angle to the axis of said conductors, the last mentioned angle being substantially less than the angle at which said outer conductor is cut, said outer member having an opening therethrough in substantial alignment with the axis of said one arm, the other arm of said dipole having a portion extending through said opening into electrical engagement with said inner conductor and in substantial axial alignment with said one arm, fastening means for securing said other arm to said inner conductor in substantial alignment with said one arm and beyond the shorter side of said outer conductor whereby said fastening means is always accessible without disassembly of said system.
